ATTORNEY.

UNITED STATES PATENT OFFICE.

MICHAEL VOLPE, OF VESTABURG, PENNSYLVANIA.

DESIGN FOR A WRENCH.

54,293.

Specification for Design.

Patented Dec. 9, 1919.

Application filed July 15, 1919. Serial No. 311,095. Term of patent 7 years.

To all whom it may concern:

Be it known that I, MICHAEL VOLPE, a citizen of the United States, residing at Vestaburg, in the county of Washington and State of Pennsylvania, have invented a new, original, and ornamental Design for a Wrench, of which the following is a specification, reference being had to the accompanying drawing, forming a part thereof.

The figure is an elevational view of the wrench showing my new design.

I claim:

The ornamental design for a wrench as shown.

MICHAEL VOLPE.
